UNITED STATES PATENT OFFICE.

ALBERT ROSENSTEIN, OF LANCASTER, PENNSYLVANIA.

DESIGN FOR A HANDLE FOR CANES OR UMBRELLAS.

SPECIFICATION forming part of Design No. 21,352, dated February 16, 1892.

Application filed December 4, 1891. Serial No. 414,059. Term of patent 3½ years.

To all whom it may concern:

Be it known that I, ALBERT ROSENSTEIN, of Lancaster, in the county of Lancaster and State of Pennsylvania, have invented certain new and useful Improvements in Designs for Umbrella, Parasol, or Cane Handles; and I do hereby declare the following to be a full, clear, and exact description of the invention, such as will enable others skilled in the art to which it pertains to make and use it, reference being had to the accompanying drawing, which forms part of this specification.

My invention relates to a new design for umbrella, parasol, or cane handles, of which the following is a specification, reference being had to the accompanying drawing, showing a part thereof.

The accompanying drawing represents the design embodying my invention.

A represents a stem, which has its upper end B bent slightly laterally, as shown, to the point C. From this point C the tapered stem D extends in the opposite direction from the

bend of the end B and inclines slightly upward and has its end E curved inward, thus forming a hand-hold. Joined to this hand-hold E is a branch F, which extends inward to one side of the bent portion B, passing around the same, its end G, extending between a stem H and the portion B, as shown. The stem H extends upward from one side of the stem A and has its end I twisted around the branch F.

The elements above described form the essential features of my invention.

Having thus described my design, what I desire to secure by Letters Patent is—

The design for a handle for umbrellas, parasols, or canes, substantially as herein shown and described.

In testimony whereof I affix my signature in presence of two witnesses.

ALBERT ROSENSTEIN.

Witnesses:

JOHN G. SCHAUER,
HERMAN A. GAUTERT.
